HEAD UNIT FOR A PEDESTAL TYPE HOLDER FOR CULINARY IMPLEMENTS

Robert A. Eckersberg and James L. Hvale, Chicago, Ill.,
assignors to Ekco Products Company, Chicago, Ill., a
corporation of Delaware

Filed Feb. 15, 1962, Ser. No. 68,847

Term of patent 14 years

(Cl. D44—29)

Fig. 1

Fig. 2

Fig. 3Fig. 4Fig. 5Fig. 6FIG. 1 is a side elevational view of a head unit for a pedestal type holder for culinary implements showing our new design.

FIG. 2 is a bottom plan view thereof.

FIG. 3 is an enlarged fragmentary section taken along line 3-3 of FIG. 2.

FIG. 4 is an enlarged fragmentary section taken along line 4-4 of FIG. 2.

FIG. 5 is a top plan view thereof.

FIG. 6 is a fragmentary section taken along line 6-6 of FIG. 5.

The essential features of our design reside in the por-

tions shown in full lines and comprise the particular depressed conic configuration of the upper face in combination with the radial slots having the form shown.

We claim:

The ornamental design for a head unit for a pedestal type holder for culinary implements, as shown and described.
